CLAIM

The ornamental design for a computer display, as shown and described.

DESCRIPTION

FIG. 1 is a perspective view of a computer display.

FIG. 2 is a front elevation view thereof.

FIG. 3 is a rear elevation view thereof.

FIG. 4 is a top plan view thereof.

FIG. 5 is a bottom plan view thereof.

FIG. 6 is a left side elevation view thereof.

FIG. 7 is a right side elevation view thereof.

FIG. 8 is a longitudinal cross-sectional view of the central part of the front elevation view thereof, taken along lines 8—8 of FIG. 2, which omits the internal structure.

FIG. 9 is a reduced front elevation view with the stand extended vertically.

FIG. 10 is a reduced right side elevation view with the stand extended vertically; and,

FIG. 11 is a reduced longitudinal cross-sectional view of the central part of the front elevation view taken along lines 11—11 of FIG. 2 with the stand extended vertically.
